Patented Mar. 15, 1921.

T. COMEAU. INVENTOR.

BY

A. Knutson Jr.

ATTORNEY.

UNITED STATES PATENT OFFICE.

TÉLESPHORE COMEAU, OF LAWRENCE, MASSACHUSETTS, ASSIGNOR OF ONE-HALF TO
FLAVIEN MOFETTE, OF LAWRENCE, MASSACHUSETTS.

CUSHION-TIRE.

1,371,863.

Specification of Letters Patent. Patented Mar. 15, 1921.

Application filed April 17, 1920. Serial No. 374,776.

To all whom it may concern:

Be it known that I, TÉLESPHORE COMEAU, a citizen of the United States, residing at Lawrence, in the county of Essex and State 5 of Massachusetts, have invented certain new and useful Improvements in Cushion-Tires: and I do hereby declare the following to be a full, clear, and exact description of the invention, such as will enable others skilled 10 in the art to which it appertains to make and use the same.

This invention relates to new and useful improvements in cushion tires and has for its primary object the provision of cushion 15 means adapted to fill a tire or shoe of the ordinary construction and efficiently support the same with the desired resiliency, thereby obviating the use of pneumatic means and the disadvantages and expense 20 attached to the latter named means.

Another object of this invention is the provision of inner and outer pads so shaped or constructed that they fully fill the casing or shoe when placed therein and have their 25 opposing faces formed to provide a chamber for the reception of a cushioning means so that said shoe or casing is afforded the desired resiliency.

A further object of this invention is the 30 provision of cushioning elements formed on one of the pads within said chamber and arranged in spaced relation to each other and engaging the other pad to permit the casing or shoe to flex when subjected to shocks 35 and jars, thereby rendering the resiliency afforded by pneumatic cushion means without the annoyance of punctures and blow-outs.

A still further object of this invention is 40 the provision of a cushion tire of the above stated character, which shall be simple, durable, and efficient, and which may be manufactured and sold at a comparatively low cost.

With these and other objects in view as 45 will become more apparent as the description proceeds, the invention consists in certain novel features of construction, combination, and arrangement of parts as will be 50 hereinafter more fully described and claimed.

For a complete understanding of my invention, reference is to be had to the fol-

lowing description, and accompanying drawing, in which:—

Figure 1 is a transverse sectional view illustrating a cushion tire constructed in accordance with my invention.

Fig. 2 is a sectional view taken on the line 3—3 of Fig. 1 looking in the direction 60 indicated by the arrow,

Fig. 3 is a sectional view taken on the line 2—2 of Fig. 1.

Referring in detail to the drawing, the numeral 1 indicates a casing or shoe of an 65 ordinary construction and which is usually employed in conjunction with a pneumatic tube, and to obviate the employment of such, I have provided inner and outer pads 2 and 3 respectively, that are so shaped or constructed as to completely fill and engage 70 the walls of the casing or shoe to efficiently support and prevent the same from collapsing under weight. The inner and outer pads extend circumferentially of the shoe 75 or casing and are preferably constructed from fabric and rubber so as to have the desired elasticity. The opposing faces of the inner and outer pads have formed therein circumferentially extending recesses 4 80 that coöperate with each other in forming a chamber 5. The recesses 4 are cut away to form V-shaped portions 6 to the cushion receiving chamber 5 to render an increased resiliency to the pads.

The outer pad 3 has formed thereon relatively spaced cushioning elements or blocks 7 that form an integral part of the inner wall of the recess 4 of said pad. The cushioning elements 7 are preferably constructed 90 from a high grade of rubber and bear against the inner wall of the recess 4 of the pad 2 and are spaced from the side walls of said recesses 4 and V-shaped portions 6 to afford air circulating spaces between the inner and outer pads and the cushioning elements 7. The cushioning elements 7 taper 95 in the direction of their free ends so as to increase the air circulating space. The inner pad 2 is provided with vent tubes 9 that 100 communicate with the cushion receiving chamber 5 to permit air to readily enter the cushion receiving chamber for the purpose of preventing overheating of the pads and the cushioning elements 7. The cushioning 105 elements 7 being spaced from the walls of

the recesses 4 of the inner and outer pads permits said cushioning elements to expand and contract under shocks and jars subjected to the casing or shoe thereby affording said 5 casing or shoe the desired resiliency.

While I have shown and described the preferred embodiment of my invention, it will be understood that minor changes in construction, combination, and arrangement 10 of parts may be made without departing from the spirit and scope of the invention as claimed.

Having thus described my invention, what I claim is:—

- 15 1. A tire cushion comprising inner and outer cushion sections adapted to have abutting engagement with each other and the wall of a shoe, said sections extending circumferentially of the shoe and having continuous recesses located in their opposing faces and cushioning blocks formed on the inner wall of the recess of the outer section and bearing against the inner wall of the recess of the inner section.
- 20 2. A tire cushion comprising inner and outer cushion sections adapted to have abutting engagement with each other and the wall of a shoe, said sections extending cir-

cumferentially of the shoe and having continuous recesses located in their opposing faces, and tapered cushioning blocks formed on the inner wall of the recess of the outer section and bearing against the inner wall of the recess of the inner section and spaced from the side walls of said recesses. 30

3. A tire cushion comprising inner and outer sections adapted to have abutting engagement with each other and to entirely fill a shoe, said sections extending circumferentially of the shoe and having continuous recesses located in their opposing faces and in alinement with each other, said recesses having their adjacent edges cut away and adapted to coöperate with each other in increasing the areas of said recesses, and 40 cushioning blocks formed on the inner wall of the recess of the outer section and bearing against the inner wall of the recess of the inner section. 45

In testimony whereof I affix my signature 50 in presence of two witnesses.

TÉLESPHORE COMEAU.

Witnesses:

WILLIAM DALTON,
JOSEPH MAXWELL.
